UNITED STATES PATENT OFFICE.

CHARLES J. HANIMAN, OF BAYONNE, NEW JERSEY, ASSIGNOR TO THE BABCOCK & WILCOX COMPANY, OF BAYONNE, NEW JERSEY, A CORPORATION OF NEW JERSEY.

AIR HEATER.

Application filed August 9, 1922. Serial No. 530,720.

My present invention relates to heat-transfer devices particularly such as are used for heating air by means of hot gases, particularly from furnaces or the like.

5 My invention will be best understood from the following description and the annexed drawings, in which Fig. 1 is a section of an illustrative embodiment of my invention; Fig. 2 is a section on the line 2—2 of Fig. 1; Fig. 3 is an enlargement of a portion of Fig. 1; and Fig. 4 is a fragment showing a modification.

Like reference characters indicate like parts in the several views.

15 In the illustrative embodiment, the hot gases pass through an inlet 10 into a flue 11 and out through an outlet 12. The flue 11 may be provided with baffles 13, 13 to cause the gases to pass back and forth through the flue 11.

In the illustrative form, the flue 11 has a top wall 14 and a bottom wall 15 connected with the side walls thereof, the top wall and the bottom wall being provided with holes 25 in alignment and extending through the walls.

Each pair of oppositely disposed holes is connected by a tube 16 which passes through the hole in the top wall 14 and rests on the bottom wall 15 concentric with the hole therein. In order to aid in the location of the lower end of the tubes 16 in proper relation to the respective openings in the lower wall 15, I preferably provide a conical cavity 17 around each of the holes in the wall 15. Preferably, the upper ends of the tubes 16 project beyond the top wall 15 in the manner shown. The tubes 16 may be a sufficiently tight fit in the holes in the wall 14 to provide a gas seal, but preferably I provide some sealing means which can be readily removed. In the illustrative form, this sealing means may be a ring 18 of asbestos packing or the like and if preferred, this ring may be held in place by a packing weight 19, as shown in Fig. 4, the flue wall surrounding the tube preferably being provided with a conical cavity in which the packing is located as illustrated. The weight of the tubes 50 16 will usually be sufficient to seal the end thereof with the lower wall 15. If desired, however, a similar sealing means can be provided around the lower ends of the tubes 16.

In the illustrative embodiment, the upper ends of the tubes 16 communicate directly with the air and the lower wall 15 is provided with a duct 20 surrounding the lower ends of all of the tubes 16 and the openings communicating with these tubes through the lower wall 15.

In practice, the hot gases pass into the inlet 10 and flow back and forth across the exterior of the tubes 16 and out of the outlet 12. At the same time, air is drawn downward through the tubes 16 by a suction device not shown, passing into the duct 20, from which it is carried to the point of use.

When used with gases laden with dust, as is usual, such an air heater has its tubes coated with dust which materially interferes with the efficiency of the device. By the arrangement shown, these tubes may be readily cleaned by drawing them out through the holes in the upper wall 14. At 16' a tube is shown partly lifted, and it will be noted that the exterior wall of the tube is, in effect, scraped by the edge of the hole in the top wall 14, which in itself will usually remove the accumulated soot and dust which will fall to the bottom wall 15 and from thence out through the openings therein. If desired, the tube 16 may be entirely withdrawn for cleaning purposes. On the other hand, the tube can be quickly returned to place, because, particularly when the sealing arrangement illustrated is used, the asbestos ring may be placed around the tube as it passes through the top wall 14 and, by reason of the conical cavity on the upper surface of that wall, this packing ring will be drawn down sufficiently tightly into the conical space to seal the exterior of the tube against gas leakage from or into the flue 11, and when the bottom of the tube reaches the lower wall 15, the weight of the tube will also give a sufficient sealing against the upper surface of this bottom wall. In order to increase the scraping portion of the upper wall, I preferably make the portion surrounding each tube in the form of a cone,

as shown at 21. It will be seen, therefore, that, in the arrangement described, the tubes may be quickly withdrawn and replaced with the minimum amount of labor and at the same time, so as to clean them effectually.

It will be understood that the embodiment of my invention may be widely varied. While I prefer to use cylindrical tubes for the air tubes, it is obvious that any other desired shape may be used. Similarly, while I prefer to utilize the weight of the tubes as a means for sealing them at the bottom, which, of course, necessitates that these tubes shall be substantially vertical, it will be obvious that the tubes may be horizontal, in which case, some sealing arrangement not dependent on the weight of the tube must be used, such as the packing ring illustrated for the top of the tube.

20 In any case, however, by my invention the tubes are made so to be quickly and readily removed, and to this end, they are only loosely connected to the heads or walls through which they pass.

25 While I have described my device as an air heater, it will be understood that it may be used for the transfer of heat from any gas to any other gas passing through the respective paths.

30 By causing the tubes to pass through the openings of one wall with a sliding fit, either with or without the prevention of movement of the tubes through the other walls in the manner described, the tubes are free to expand individually or collectively through the openings in which they slide. Such an arrangement is particularly useful with an air heater where it is desired to blow from the tubes soot or dust which has collected therein, and where the steam usually used for this operation causes a relative expansion of the tubes thus cleaned. Furthermore, by providing means for sealing the sliding joint and maintained in sealing engagement therewith under both expanded and unexpanded conditions of the tube in the described manner, the tubes maintain a substantially gas tight fit under all conditions of operation.

35 I claim:

1. In an air heater, a gas flue having an inlet and an outlet and having a plurality of pairs of holes in alignment in its top and bottom walls, and tubes extending vertically across the flue, each tube connecting a pair of said holes and extending into the hole in the top wall with a relatively loose fit and being unconnected thereto, with the lower end of the tube abutting against the interior of the bottom wall of the flue and held there by the weight of the tube, the interior face of the top wall of the flue having sloped projections surrounding the tubes.

2. In an air heater, a chamber provided with end walls each provided with a plurality of openings, a plurality of tubes, the openings in one end wall being large enough to permit said tubes to pass through, the openings in the other end wall comprising a conically shaped portion and being insufficiently large to permit the tubes to pass entirely through said end wall the end portions of said tubes co-acting with the openings in said walls, each tube passing through an opening in one wall with a sliding fit whereby the tube is free to expand therethrough, and means surrounding the tube for sealing said sliding joint and maintained in sealing engagement therewith under both expanded and unexpanded conditions of the tube.

3. In an air heater, a chamber provided with end walls each provided with a plurality of openings, a plurality of tubes; the openings in one end wall being large enough to permit said tubes to pass through, the openings in the other end wall comprising a conically shaped portion and being insufficiently large to permit the tubes to pass entirely through said end wall, the end portions of said tubes coacting with the openings in said walls, each tube passing through an opening in one wall with a sliding fit whereby the tube is free to expand therethrough and held against movement through the other wall, and means surrounding the tube for sealing said sliding joint and maintained in sealing engagement therewith under both expanded and unexpanded conditions of the tube.

4. In an air heater, a gas flue having an inlet and an outlet and having a plurality of pairs of holes in alignment in its top and bottom walls, and tubes extending vertically across the flue, each tube connecting a pair of said holes and extending into the hole in the top wall with a relatively loose fit and being unconnected thereto, the holes in said bottom wall being surrounded by conical cavities with the greater diameter at the top, the lower ends of said tubes being seated against said conical cavity and held in position by gravity.

5. In a heat interchanger, a flue having an inlet and an outlet and having a plurality of pairs of holes in alignment in its opposite walls, tubes extending across the flue, each tube connecting a pair of said holes and extending into and through at least one of said holes with a relatively loose fit and being unconnected thereto, said tube being adapted to be withdrawn through said hole, a packing between the tube and the exterior of the wall of the flue, and a packing weight surrounding the tube and resting on said packing to retain the same in position.

6. In a heat interchanger, a flue having an inlet and an outlet and having a plurality of pairs of holes in alignment in its opposite walls, tubes extending across the flue, each tube connecting a pair of said holes and extending into and through at least one of said holes with a relatively loose fit and being unconnected thereto, said tube being

adapted to be withdrawn through said hole, the flue wall surrounding the tube being formed with a conical cavity, a packing seated in said conical cavity, and a packing weight surrounding the tube and resting on said packing to retain the same in position. 10

CHARLES J. HANIMAN.
